(57) **CLAIM**

The ornamental design for the wall junction, as shown and described.

DESCRIPTION

FIG. 1 is a front perspective view of a first embodiment of the wall junction illustrated with a panelized wall system.

FIG. 2 is a front perspective view of the wall junction in FIG. 1.

FIG. 3 is a front view of the wall junction in FIG. 1.

FIG. 4 is a rear view of the wall junction in FIG. 1.

FIG. 5 is a left side view of the wall junction in FIG. 1. The right side view is a mirror image of the left side view.

FIG. 6 is a top view of the wall junction in FIG. 1. The bottom view is a mirror image of the top view.

FIG. 7 is a front perspective view of a second embodiment of the wall junction illustrated with a panelized wall system.

FIG. 8 is a front perspective view of the wall junction in FIG. 7.

FIG. 9 is a front view of the wall junction in FIG. 7.

FIG. 10 is a rear view of the wall junction in FIG. 7.

FIG. 11 is a left side view of the wall junction in FIG. 7. The right side view is a mirror image of the left side view.

FIG. 12 is a top view of the wall junction in FIG. 7; and,

FIG. 13 is a bottom view of the wall junction in FIG. 7.

The broken lines are for illustrative purposes only and form no part of the claimed design.
